US0D1075676S

(12) **United States Design Patent** (10) **Patent No.:** **US D1,075,676 S**
(45) **Date of Patent:** **** May 20, 2025**

(54) **MAGNET FOR STEEL-RULE DIE ASSEMBLY**

(71) Applicant: **DIEBEC MATRICES LTÉE**,
Pointe-Claire (CA)

(72) Inventors: **Tommaso Mancuso**, Pointe-Claire
(CA); **Paolo Quercia**, Pierrefonds (CA);
José Sylvestre, Pointe-Claire (CA)

(73) Assignee: **DIEBEC MATRICES LTÉE** (CA)

(**) Term: **15 Years**

(21) Appl. No.: **29/833,682**

(22) Filed: **Apr. 6, 2022**

Related U.S. Application Data

(63) Continuation of application No. 35/508,768, filed on Sep. 6, 2019 (U.S. filing date under 35 U.S.C. 384), and having an international filing date of Sep. 6, 2019, now abandoned.

(57) **CLAIM**

The ornamental design for a magnet for steel-rule die assembly as shown and described.

DESCRIPTION

FIG. 1 is a front perspective view of the article;
FIG. 2 is a front plan view thereof;
FIG. 3 is a rear plan view thereof;
FIG. 4 is a left side view thereof;
FIG. 5 is a right side view thereof;
FIG. 6 is a top view thereof;
FIG. 7 is a bottom view thereof; and,
FIG. 8 is a perspective view shown in an environment.
In the drawings, the broken lines are for the purpose of illustrating portions of the nose guard that form no part of the claimed design.

1 Claim, 8 Drawing Sheets
